UNITED STATES PATENT OFFICE.

CARL SCHANTZ, OF FREIBURG, GERMANY.

MANUFACTURE OF BICHLOORID OF MERCURY.

1,373,357.

Specification of Letters Patent. Patented Mar. 29, 1921.

Application filed December 6, 1920. Serial No. 428,553.

To all whom it may concern:

Be it known that I, CARL SCHANTZ, of Freiburg, Germany, a citizen of the German Republic, have invented certain new and useful 5 improvements in the manufacture of Bichlorid of Mercury, of which the following is a specification.

For the manufacture of bichlorid of mercury, from mercury and chlorin, a large excess of dry gaseous chlorin is generally used and the temperature is carried to the degree at which the resultant bichlorid is sublimated. In another process, chlorin under pressure is introduced into a closed vessel 15 containing the mercury in motion in a gaseous or liquid medium, and the conversion takes place at a temperature below the vaporization point of the chlorid. If the medium is water, and the temperature 20° C. 20 (which must not be exceeded, otherwise the water will not absorb chlorin), the heat of formation requires the use of so much water that the process is too expensive for dealing with large quantities of mercury.

According to my invention these disadvantages are obviated. The mercury is dropped through a chlorin atmosphere under slight pressure into a liquid, which absorbs little or no chlorin and the temperature of 30 which is preferably kept down to near its boiling point, as by admission of fresh cold liquid. The mercury forms bichlorid in falling through the chlorin atmosphere, and the bichlorid is dissolved in the liquid.

Apparatus for the purpose is shown in the annexed drawing, in cross section.

The drum F, containing the chlorin, the mercury Q and a body of liquid F¹ is rotatable and has inwardly directed blades, which 40 lift the mercury out of the liquid F¹ and drop it back through the chlorin atmosphere into the liquid F¹. The speed of the drum may be sufficiently high to cause the blades to project the mercury more or less 45 across the interior of the drum, so that it takes a longer path through the chlorin.

Examples of liquids which do not appreciably absorb chlorin are solutions of chlorids, or hot water, which in the course 50 of the process is converted into a concentrated solution of mercury bichlorid. The heat of formation given off to the liquid soon raises its temperature to a point at which there can be no formation of calomel. 55 Even if a cold saturated solution of mercury bichlorid is used, most of the sublimate

formed will be dissolved, by reason of the increase of temperature which occurs. Consequently metallic mercury will always be carried back into the chlorin atmosphere. 60

By regulating the supply of fresh liquid the rate of the conversion process can be controlled. The process is practicable at a high temperature, provided the same does not exceed the boiling point of the liquid. 65

The dissolved sublimate crystallizes out when the liquid is cooled, except in regard to that proportion thereof which saturates the cold solution, and the product is obtained in a finely crystalline state. The 70 liquid can be re-used for cooling and renewing the bath. Owing to the comparatively high temperature of the bath the same is nearly free from chlorin.

As an example, 50 kg. of mercury are 75 placed in a bath of 50 l. of a saturated solution of mercury bichlorid and the chlorin is introduced at a pressure of about half an atmosphere, the mercury being lifted and dropped through the chlorin as described. 80 By admission of cold solution the temperature is kept down to about boiling point and when the conversion is complete the quantity of liquid will be about 150 l. Of this, about 50% are mercury bichlorid 45% being 85 newly produced in the course of the process. On discharging and cooling the solution, all the newly produced bichlorid crystallizes out, and the liquid can be re-used.

What I claim as my invention and desire 90 to secure by Letters Patent of the United States is:—

1. The process of producing mercury bichlorid which consists in passing mercury through an atmosphere of chlorin into a 95 bath of a liquid which is not an active absorbent of chlorin.

2. The process of producing mercury bichlorid which consists in passing mercury through an atmosphere of chlorin into a 100 bath of a liquid which is not an active absorbent of chlorin and cooling said bath so that its temperature is kept down approximately to boiling point.

3. The process of producing mercury bichlorid which consists in passing mercury through an atmosphere of chlorin into a bath of a liquid which is not an active absorbent of chlorin and cooling said bath by admission of fresh cold liquid so that its temperature is kept down approximately to 105 boiling point.

4. The process of producing mercury bi-chlorid which consists in passing mercury through an atmosphere of chlorin under moderate pressure into a bath of a liquid which is not an active absorbent of chlorin.
5. The process of producing mercury bi-chlorid which consists in passing mercury through an atmosphere of chlorin under moderate pressure into a bath of a liquid which is not an active absorbent of chlorin

and cooling said bath by admission of fresh cold liquid so that its temperature is kept down approximately to boiling point.

In witness whereof I have signed this specification in the presence of two witnesses.

DR. CARL SCHANTZ.
